UNITED STATES PATENT OFFICE.

EDWARD BEACH GALLAHER, OF PHILADELPHIA, PENNSYLVANIA.

DESIGN FOR A VEHICLE-BODY.

SPECIFICATION forming part of Design No. 35,109, dated September 17, 1901.

Application filed August 15, 1901. Serial No. 72,196. Term of patent 7 years.

To all whom it may concern:

Be it known that I, EDWARD BEACH GALLAHER, a citizen of the United States, and a resident of Philadelphia, in the county of Philadelphia and State of Pennsylvania, have invented and produced an original Design for a Vehicle-Body, of which the following is a specification, reference being had to the accompanying drawings, forming a part thereof.

Figure 1 is a side view of a vehicle-body, showing my new design. Fig. 2 is a rear view, and Fig. 3 is a front view, of the same.

As shown in the drawings, the leading or material feature of my design consists in a vehicle-body having a front seat portion *a*, a rear seat portion *b*, and a forwardly-extended footboard having a horizontal portion *c* and an upwardly-inclined portion *d*, the front seat portion *a* having inwardly-curved front

and rear walls *e f* and a flat top *g* and the rear seat portion *b* having inwardly-curved front and rear walls *h i* and a flat top *j*. A bead *k* runs along the front inwardly-curved wall *h* of the rear seat portion *b* and along the top of the portions *c d* of the footboard at each side of the vehicle-body.

What I claim is—

The design for a vehicle-body, substantially as herein shown and described.

In testimony that I claim the foregoing as my invention I have signed my name, in presence of two witnesses, this 10th day of July, 1901.

EDWARD BEACH GALLAHER.

Witnesses:

ROBERT B. SEWARD,
M. A. STONE.
